UNITED STATES PATENT OFFICE.

CHARLES E. GODLEY, OF DETROIT, MICHIGAN.

DESIGN FOR A VEHICLE-LAMP.

46,495.

Specification for Design.

Patented Oct. 6, 1914.

Application filed July 3, 1914. Serial No. 848,957. Term of patent 14 years.

To all whom it may concern:

Be it known that I, CHARLES E. GODLEY, a citizen of the United States, residing at Detroit, in the county of Wayne and State of Michigan, have invented a new, original, and ornamental Design for Vehicle-Lamps, particularly tail-lamps for automobiles, of which the following is a specification, reference being had to the accompanying drawing, forming part thereof.

Figure 1 of the drawing is a side elevation and Fig. 2 a front elevation of a vehicle lamp, showing my new design.

I claim:

The ornamental design for a vehicle lamp, as shown.

CHARLES E. GODLEY.
